(57) **CLAIM**

The ornamental design for a plug for a pipe coupling, as shown and described.

DESCRIPTION

FIG. 1 is a perspective view of a plug for a pipe coupling showing my new design;

FIG. 2 is a front elevational view thereof;

FIG. 3 is a top plan view thereof;

FIG. 4 is a left side elevational view thereof;

FIG. 5 is a right side elevational view thereof; and,

FIG. 6 is a front cross-sectional taken along line 6-6 in FIG. 4;

A rear elevational view is omitted as it appears symmetrical with the front view. A bottom plan view is omitted as it appears to be the same as the top plan view.

(Continued)

The broken lines show portions of the design that form no part the claimed design.
